RICHARD THOMSON GLASCODINE, OF LONDON, ENGLAND

CENTRAL BUFFING AND DRAWGEAR

Application filed November 29, 1929, Serial No. 410,558, and in Great Britain May 14, 1929.

This invention relates to central buffing and draw gear for railway vehicles carried by bogie trucks.

The object of the invention is to provide an improved arrangement of buffing and draw springs.

It has been heretofore usual to provide buffing and draw springs in association with the draw rod at the rear of the vehicle headstock between the headstock and the centre pivot pin of the bogie truck supporting the corresponding end of the vehicle. The space available however is not always sufficient to enable sufficiently powerful buffing and draw springs to be provided.

According to the present invention buffing and draw springs located as heretofore usual between the said bogie centre pin and the vehicle headstock are associated with other buffing and draw springs located at the rear of the said bogie centre pin, means being provided for so connecting the one arrangement of buffing and draw springs to the other that all the said buffing and draw springs function together when either buffing or drawing. In this way it is possible to provide buffing and draw gear with springs adapted to give the resistance desirable under the heavy blow to which high capacity vehicles are subjected.

With advantage the buffing and draw spring arrangement located at the inner side of the headstock is combined with an additional buffer spring or springs located at the front of the headstock and so arranged as to come into action upon inward movement of the coupling head.

Preferably the springs employed are rubber springs namely springs consisting of concentric annular rings or frames of rubber moulded to metal plates that maintain the rubber rings the desired distance apart, metal dividing plates or rings being interposed between the several units of said spring. The highest efficiency will be obtained by using such known type of springs although the inven-

tion is not restricted to the use of rubber springs alone, as in some cases rubber springs may be used in combination with steel springs but in such a combination the rubber springs should be so arranged as to prevent the steel springs being pressed home.

In carrying out the invention the draw rod at the front of the bogie centre pivot pin is connected as by cross members and substantial connecting rods to a second draw rod located at the rear of the bogie centre pivot pin and each said draw rod has mounted tandem-wise thereon a plurality of buffing and a plurality of draw springs so associated with compression plates and abutment members that when buffing the buffing springs function in parallel and when drawing the draw springs likewise function in parallel; alternatively the arrangement of the sets of springs arranged tandem-wise around the draw rods may be so combined with intermediate pressure plates and sleeves that when either buffing or drawing one spring or a certain number of the springs comes or come first into action after which all the springs are compressed in parallel.

Fig. 1 of the accompanying drawing illustrates in sectional plan a construction of buffing and draw gear embodying the invention.

Fig. 2 is a similar view to Fig. 1 illustrating another construction of the improved buffing and draw gear.

In the constructions illustrated all the springs are india-rubber springs of the kind before-mentioned.

Referring to the construction shown in Fig. 1, the draw rod 1 that is pivoted at 2 to the shank 3 of the coupler head 4 is connected by cross heads 5 and distance tie-rods 6 to a second draw rod 7 located axially at the rear of the bogie centre pivot 8. Each draw rod 1 and 7 has fitted thereon two india-rubber springs 9 and 10 located one in front of the other. The spring 9 of each set is located between a front compression plate 11

80

90

which normally bears on fixed abutments 12, and an intermediate compression plate 13. The spring 10 of each set is arranged between an end compression plate 14 that normally bears on fixed abutments 15, and a compression plate 16 pressure upon which is transmitted from the other end compression plate 11 through a sleeve 17. The intermediate compression plate 13 is mounted to slide on the said sleeve 17.

In the example illustrated the sleeve 17 is formed in one with the compression plate 16. A sleeve 18 that houses the rear spring 10 is located between the sliding compression plate 13 and the compression plate 14 of the spring 10. As shown the sleeve 18 is formed in two parts, one part being formed in one with the compression plate 13 and the other part being formed in one with the compression plate 14.

The shank 3 of the coupler head abuts against the compression plate 11 and the arrangement is such that the inner spring 10 of each pair of springs comes into action first 25 when either buffing or drawing until the two parts of the sleeve 18 abut one against the other after which all the springs are compressed in parallel.

19 indicates an additional india-rubber buffer spring located in a casing 20 at the front of the vehicle headstock. This spring is adapted to be compressed upon inward movement of the coupling head 4 through a compression plate 21 having an extension that 25 projects forwardly from the fixed casing 20.

The springs 10 which are first in action may be so designed as to be more sensitive to resist relatively light loads than the other springs 9 which come into action later and 45 the initial compression to which all the springs at the inner side of the headstock are subjected when normal may be so determined as to present any resistance desired and found suitable in practice.

55 In the construction shown in Fig. 2, the draw rod 1 is fitted with two india-rubber springs 22 and the rear draw rod 7 which is connected to the draw rod 1 in like manner to that already described with reference to Fig. 1, is fitted with a third india-rubber spring 23. In this construction all the springs function in parallel from the start. Each spring is arranged between compression plates 23 that normally bear against fixed 55 abutments 24. Between the adjacent compression plates 23 of the two springs 22 on the draw rod 1 a thrust-transmitting nut or collar 25 is fixed on the said draw rod.

60 The improved spring arrangement provides an efficient and satisfactory range wherein the resistance both in buffing and drawing is sensitive and yet capable of giving definite movement under the heaviest loads.

65 What I claim is:—

1. Central buffing and draw gear for railway vehicles carried upon bogie trucks, a coupler head, a draw rod to the front end of which the said coupler head is pivoted, a plurality of india-rubber buffing and draw 70 springs mounted tandem-wise on said draw rod, a second draw rod located axially in line with said first-mentioned draw rod but located at the rear of the centre pivot pin of a supporting bogie, means rigidly connecting together the two said draw rods and bridging the said centre pin, and a plurality of india-rubber buffing and draw springs mounted tandem-wise on said second draw rod. 75

2. Central buffing and draw gear for railway vehicles carried upon bogie trucks, a coupler head, a draw rod to the front end of which said coupler head is pivoted, a plurality of india-rubber springs arranged in 85 sets tandem-wise around said draw rod, for each of said sets of springs a front pressure plate, a fixed abutment against which said front pressure plate bears when drawing, a rear pressure plate, a fixed abutment against which said rear pressure plate bears when buffing, an intermediate compression plate, a sleeve that transmits pressure to said intermediate compression plate after one spring of the said set has been compressed to a limited 95 extent, a compression plate mounted to slide on said sleeve, a sleeve located between the said sliding compression plate and the said end pressure plate of the spring that first comes into action, a second draw rod located 100 axially in line with said first-mentioned draw rod but located at the rear of the centre pivot pin of a supporting bogie, means rigidly connecting together the two said draw rods and bridging the said centre pin, a plurality 105 of india-rubber springs arranged in sets tandem-wise around said second draw rod, for each of said last-mentioned sets of springs a front pressure plate, a fixed abutment 110 against which said front pressure plate bears when drawing, a rear pressure plate, a fixed abutment against which said rear pressure plate bears when buffing, an intermediate compression plate, a sleeve that transmits pressure to said intermediate compression 115 plate after one spring of the said set has been compressed to a limited extent, a compression plate mounted to slide on said sleeve, and a sleeve located between the said sliding compression plate and the said end pressure plate of the spring that first comes into action. 120

3. Central buffing and draw gear for railway vehicles carried upon bogie trucks, comprising a draw rod, pivoted to the coupler head shank, india-rubber springs mounted on said draw rod at the rear of the vehicle headstock and in front of the bogie centre pivot, fixed front and rear abutments for said springs secured to the vehicle centre sills, 125 130

a second draw rod at the rear of said bogie centre pivot, india-rubber springs on said second draw rod, fixed front and rear abutments for said springs secured to the vehicle 5 centre sills, and tie rods bridging said bogie centre pivot and connecting said draw rods to ensure the simultaneous operation of said front and rear springs when either buffing or drawing.

10 4. Central buffing and draw gear for railway vehicles carried upon bogie trucks, comprising a draw rod, pivoted to the coupler head shank, india-rubber springs mounted on said rod at the rear of the vehicle head- 15 stock and in front of the bogie centre pivot, abutment plates for said springs floating on the draw rod, fixed front and rear abutments for said plates secured on the vehicle centre sills, a second draw rod at the rear of said 20 bogie centre pivot, india-rubber springs on said draw rods, abutment plates for said springs floating on said draw rod, fixed front and rear abutments for said plates to the vehicle centre sills and tie rods bridging said 25 bogie centre pivot and connecting said draw rods to ensure the simultaneous operation of said front and rear springs when either buffing or drawing.

5. Central buffing and draw gear for rail- 30 way vehicles carried upon bogie trucks comprising a draw rod pivoted to the coupler head shank, two sets of india-rubber springs mounted on said draw rod at the rear of the vehicle headstock and in front of the bogie 35 centre pivot, fixed front, central, and rear abutments for said springs secured to the vehicle centre sills, a second draw rod at the rear of said bogie centre pivot, a set of india-rubber springs on said draw rod, fixed front and 40 rear abutments for said set secured to the vehicle centre sills, and tie rods bridging the bogie centre pivot and connecting said draw rods whereby said three sets of india-rubber springs are simultaneously compressed in 45 parallel when either buffing or drawing.

In testimony whereof I affix my signature.
RICHARD THOMSON GLASCODINE.
